INVENTOR:

Samuel Hulbert

United States Patent Office.

SAMUEL HULBERT, OF OGDENSBURG, NEW YORK.

Letters Patent No. 78,457, dated June 2, 1868.

IMPROVEMENT IN PLOUGHS.

The Schedule referred to in these Letters Patent and making part of the same.

TO ALL WHOM IT MAY CONCERN:

Be it known that I, SAMUEL HULBERT, of the village of Ogdensburg, in the county of St. Lawrence, State of New York, have invented a new and improved Mode of Fastening the Agricultural Plough together without bolts by a dove-tail lock and key; and I hereby declare that the following is a full and exact description thereof, reference being had to the accompanying drawings making a part of this specification, in which—

Figure 1 represents the land-side, showing a cavity to receive the flange of the mould-board at *a*.

Figure 2 represents a section of the land-side, showing at *b* the cavity and the flange which forms the tenon of the dove-tail.

Figure 3 represents a section of the mould-board and its flange at the left, with a hook at the right forming the dove-tail, as shown at *c*.

Figure 4 represents the section of the land-side and the section of the mould-board put together, showing a vacancy ready to receive the key at *d*.

Figure 5 represents the lower portion of the land-side, where the plough-point goes on it, having a hole through which the hook of the plough-point passes, and a hook on the land-side, showing a vacancy for the key at *e*.

Figure 6 represents the plough-point in a manner showing its hook at *f*.

Figure 7 represents the land-side and plough-point put together, the hook passed through the hole in the land-side leaving a place for the key at *g*.

Figure 8 represents the plough entire, with the brace-rod across from the land-side to the flat loop on the inside of the mould-board, the brace-rod having screw-nuts, so that the plough may be made wider or narrower at pleasure. This rod also holds the handles, as shown at *h*.

Figure 9 represents the working-side of the plough, the mould-board, and point, without any bolt-heads, having a uniform smooth surface, its surface being straight lines longitudinal on the transverse straight lines, forming an angle of about fifty degrees throughout with the longitudinal.

The same kind of dove-tail lock and key is used for the double-mould plough and single cultivator, only the standard has a slot-hole through the centre to receive the two flanges where the mould-boards come together, and the cultivator sides are so constructed that they can be used when the mould-boards are taken off, the same point, standard, beam, and handles answering for either.

Figure 10 represents a section of the standard for the double-mould plough, the slot-hole represented at *i*.

Figure 11 represents the mould-board placed on the standard, their flanges through the slot-hole at *j* ready to receive the key at *k*.

Figure 12 represents the inside of a mould-board, with its flange at *l*, its hooks at *m m*, its loops at *n n*.

Figure 13 represents one of the cultivator sides, so constructed as to go on the double mould-board plough, when the mould-boards are taken off, and made so as to cut the weeds in a sliding manner at *o*. They are used, also, for digging potatoes.

I claim the improved manner of fastening the plough and cultivator together, separately and connectedly, in manner and for the purposes as herein described and constructed.
